United States Patent Office

Des. 229,804
Patented Jan. 8, 1974

229,804

CHAIR

Herman A. Hassinger, Moorestown, N.J., assignor to
Hassinger & Schwam Associates, Inc., Philadelphia, Pa.

Filed May 30, 1972, Ser. No. 258,189

Term of patent 14 years

Int. Cl. D6—01

U.S. Cl. D6—78

FIG. 2.

FIG. 5.

FIG. 1.

FIG. 4.

FIG. 3.

FIG. 6.

FIG. 1 is a front elevation of a chair embodying my new design;

FIG. 2 is a plan view of the chair;

FIG. 3 is a lefthand side elevation;

FIG. 4 is a rear elevation;

FIG. 5 is an inverted plan as seen from the line 5—5 in FIG. 1;

FIG. 6 is a transverse sectional view as seen from the line 6—6 in FIG. 1.

The righthand side elevation is a mirror image of the lefthand side elevation.

I claim:

The ornamental design for a chair, as shown and described.
